UNITED STATES PATENT OFFICE.

JOHN EVERETT SURFUS, OF OREGON CITY, OREGON, ASSIGNOR OF ONE-HALF TO EVA W. SURFUS, OF OREGON CITY, OREGON.

AUTOMATIC ROLL-SKINNING APPARATUS.

Application filed February 28, 1925. Serial No. 12,260.

To all whom it may concern:

Be it known that I, JOHN E. SURFUS, a citizen of the United States, residing at Oregon City, in the county of Clackamas 5 and State of Oregon, have invented certain new and useful Improvements in Automatic Roll-Skinning Apparatus, of which the following is a specification.

The invention has for its object to provide a simple and effective means for automatically cutting the lap of pulp sheets formed on the presser roll of so-called "wet machines," that operation being incident in the skinning of such pulp sheet from the 10 roll on which it is formed and which said operation, despite efforts to produce mechanical means for the purpose, is at present most efficiently performed only by an individual hired for that specific purpose and 15 who accomplishes that purpose by hand with a hand tool known in the art as a "skinning-stick."

In these "wet-machines" the pulp sheet is formed on the upper one of a pair of upper 20 and lower presser rolls, that roll being vertically movable in guides so that the ever increasing thickness of the pulp sheet accounted for by the winding on of successive 25 thicknesses of the material may be accommodated. Under the present method, the roll Skinner observes the accumulation of thickness of the pulp sheet and at the proper moment cuts across the same with the skinning-stick to skin the sheet from the 30 roll on which it is formed.

It is to remedy the above mentioned expensive and more or less impractical operation that my invention is addressed and in its more detailed nature the said invention 35 seeks to provide a simple skinning device, pressure actuated and spring returned, and the functioning of which is controlled by movement of the upper presser roll of the machine to thereby assure the cutting of the 40 lap of pulp sheet at the proper time.

With the above and other objects in view that will hereinafter appear, the invention further resides in those novel details of construction, combination, and arrangements of parts, first fully described in the following detailed description, then particularly pointed out in the appended 50 claims, reference being had to the accompanying drawing, in which:—

Figure 1 is a somewhat diagrammatic front elevation and part section illustrating the application of the invention.

Figure 2 is vertical cross section taken on the line 2—2 on Figure 1.

Figure 3 is a detail perspective view of 60 the cutter carrying plunger.

In the drawing 1 and 2 indicate the upper and lower press rolls of the pulp or so-called "wet" machine, and 3 and 4 the trunnions thereof respectively.

A cylindrical plunger housing 5 is mounted above the upper press roll 1 upon which the pulp layers accumulate to form the pulp sheet which is to be skinned from that roll, in the manner and position diagrammatically illustrated in Figure 1 of the drawing. The housing 5 is hollow to provide a cylindrical bore or plunger guideway 6 and has the lower portion of the wall thereof slotted throughout its length as indicated at 7 in Figures 1 and 2.

One end of the housing 5 is provided with an enlarged portion for providing an enlarged air chamber 8 in communication with the plunger guide 6, the purpose for which will later appear, and an air induction portion 9 of substantially the same diameter of the said guide and which communicates with the said enlarged chamber.

A compressed air line is connected in communication with the air portion 9, which said communication is controlled by the valve 10 which may be of any approved type such as is spring held to a normally closed condition.

Thus it will be understood that compressed air injection into the chamber 8 is normally closed off, and it will herein-after appear that means is provided, controlled by upward movement of the roll 1

effected by pulp layer accumulation, for so actuating that valve, at the desired moment, to open compressed air communication but momentarily, so that the actual skinning action alone is air pressure effected and not the resetting of the parts to their normal position.

100 The resetting of the parts to their normal position in a manner soon to be described and which provides for a more efficient and economic manipulation than has heretofore been possible.

In Figure 1 of the drawing I have diagrammatically illustrated one simple means of effecting the desired momentary valve actuation, it being understood that any

other suitable means may be employed, and I do not wish to be limited to the employment of the specific means shown.

In the illustration referred to I have shown a weighted lever 11, pivoted as at 12 in position for being raised to an elevation above the spring extended stem of the valve 10 and dropped to effect a striking and momentary depression of that stem to momentarily unseat or open the valve, a spring 13 serving to normally hold that lever in the normal position illustrated in the said Figure 1.

For elevating the lever 11 to a suitable elevation and dropping the same onto the valve stem I provide a rod 14 vertically movable in a suitable bearing as indicated, the said rod having at one extremity a rule jointed portion 15 and being connected by the crank 16 and link devices 16 to be moved upwardly with and under the control of one trunnion of the upper press roll 1.

The pulp sheet has been designated 17.

A free plunger 18, cylindrical in shape and of a size for more or less snugly-slidably fitting the guide 6, is provided and has secured thereto the skinning knife 19 sharpened to a cutting edge as at 20 and which is so shaped and secured to the plunger as to provide a slot engaging guide fin 21. As indicated in Figures 1 and 2 the knife 19 projects through the longitudinal slotway 7 and engages the upper roll 1 so as to effectively cut the pulp sheet when the momentary air pressure impulse is imparted to the plunger to cause said knife to traverse the said pulp sheet.

A cushion spring 22 is positioned in the end of the guide 6 opposite that which communicates with the chamber 8 and that spring may or may not be carried by the guide end closing plug 23 as desired. As before stated the compressed air injection is but momentary and ceases just before the plunger completes its cross travel so that when the plunger 18 does complete such travel and engages the spring 22 it will be caused to rebound to its initial normal position illustrated in Figure 1.

The operation of the invention is as follows:

As the pulp layer accumulation attains the desired thickness to form the pulp sheet the upper press roll 1 will have been lifted thereby an amount equivalent to the thickness of that sheet.

As the upper roll 1 rises, its trunnion 3 engages the first rockable lever of the devices 16 and, through the other lever and link thereof, effects an elevation of the rod connection 14. As the rod 14 rises, its rule jointed end 15 will engage and lift the free end of the pivoted and weighted lever 11 which, when elevated to the proper height will become disengaged from the end 15 and

fall with force upon the valve stem, effecting a momentary opening of the valve but rebounding to the normal position above the valve stem as indicated in Figure 1 by reason of the provision of the spring 13.

The momentary blast of air will be directed against the free plunger 18 and effect a driving of the knife 19 across the roll 1 to cut the pulp sheet, from the full line position to the dot and dash position indicated in Figure 1.

When the plunger 18 reaches the limit of its stroke, as indicated by the dot and dash lines above mentioned, it will have engaged and stored up sufficient energy in the spring 22 to cause it to rebound to the normal position indicated in full lines in the said Figure 1.

As the roll 1 descends to the normal lowered position the rod 14 is lowered to its normal position, the rule joint end 15 collapsing to permit passing of the end of the lever 11 and falling to its normal position after passing that lever end.

By reason of providing the quick momentary air blast the pulp sheet is positively cut at the desired moment without variation due to uncertain gear meshing or other controlling transmissions heretofore attempted for the purposes here addressed. Also, by providing the slot 7 and directing the same at the cut the skinning action is greatly facilitated by the air blast.

It will be observed by reference to Figure 1 that the plunger 18, when in its normal at rest position, projects into the chamber 8. The provision of such a chamber will effectively serve to prevent air cushioning of the plunger such as might tend to discontinue its rebound short of the return to absolute normal.

In the foregoing description I have disclosed a simple, practical and efficient automatic lap cutter, more compact than other devices addressed to the same purpose, and which is automatically operable for efficiently and uniformly cutting the pulp sheets, thus eliminating the need of the hand employed to skin the rolls by hand, and the structural details of which and the manner of operation will be readily apparent to those skilled in the art to which the invention relates.

What I claim is:

1. In roll skinning mechanism of the class described, a free piston carrying a skinning knife, a guide in which said piston is movable across the roll on which the pulp sheet accumulates for engaging and cutting that sheet, means at one end of said guide for imparting a driving impulse to said piston to propel it in the sheet cutting direction, and means at the other end of said guide for causing a rebound of said piston to its normal position.

2. In roll skinning mechanism of the class described, a free piston carrying a skinning knife, a guide in which said piston is movable across the roll on which the pulp sheet accumulates for engaging and cutting that sheet, means for injecting an air blast at one end of said guide for imparting a driving impulse to said piston to propel it in the sheet cutting direction, and a spring device at the other end of said guide for causing a rebound of said piston to its normal position.
3. In roll skinning mechanism of the class described, a free piston carrying a skinning knife, a guide in which said piston is movable across the roll on which the pulp sheet accumulates for engaging and cutting that sheet, means for injecting an air blast at one end of said guide for imparting a driving impulse to said piston to propel it in the sheet cutting direction, and a spring device at the other end of said guide for causing a rebound of said piston to its normal position, said guide being slotted to permit projection of the skinning knife and said slot being directed toward the line of cut of the said knife.
4. In roll skinning mechanism of the class described, a free piston carrying a skinning knife, a guide in which said piston is movable across the roll on which the pulp sheet accumulates for engaging and cutting that sheet, means for injecting an air blast at one end of said guide for imparting a driving impulse to said piston to propel it in the sheet cutting direction, and a spring device at the other end of said guide for causing a rebound of said piston to its normal position, the said guide having an enlarged portion forming an air chamber into which the plunger projects when in its normal position.
5. In combination with the upper and lower press rolls of a pulp machine, one of which is vertically movable relatively to the other and adapted to receive accumulating layers of pulp; a free piston carrying a skinning knife, a guide in which said piston is movable across the roll on which the pulp sheet accumulates for engaging and cutting that sheet, means for injecting an air blast at one end of said guide for imparting a driving impulse to said piston to propel it in the sheet cutting direction, and a spring device at the other end of said guide for causing a rebound of said piston to its normal position, the said air blast injecting means including a control valve and means actuated by and at a predetermined moment of the upward travel of the movable press roll for momentarily opening said valve.

JOHN EVERETT SURFUS.
